LOCKING DEVICE FOR THREAD CLEARERS

Samuel Hyslop, Newton, Mass.

Application October 15, 1932. Serial No. 637,945

3 Claims. (Cl. 28—64)

This invention relates to machines for winding thread or yarn and its object is to provide an improvement upon the construction described in my prior Patents Numbers 1,499,929 and 1,740,242, 5 designed to prevent breaking of the thread or yarn in certain types of machines when they are started up.

Referring to the drawing:

Fig. 1 is a face view of my novel thread or yarn 10 clearer;

Fig. 2 a side view thereof in operative position;

Fig. 3 a similar view partly in section, showing 15 the collar locking member in operative position;

Fig. 4 a face view of the same;

Figs. 5—6 plans respectively of the collar and 20 ring clearing members;

Fig. 7 a side elevation of the slot reducing ring; and

Fig. 8 a similar view of said member at a right 25 angle to the position of Fig. 7.

Referring to Figs. 1 to 4 of the drawing, my novel slab catcher comprises a base 1 of suitable material, herein substantially rectangular in outline, and of metal.

The base has, at a suitable point thereon, any convenient means 2 for locking it to the rail or rod 3, to which such devices are usually secured, of a winding machine, not shown.

The base, Figs. 1, 2, may be provided with a suitable number, herein two, of yarn guides 4 of any desired construction. The slab catching elements proper herein comprise first (Figs. 1, 4, 5, 6) a ring 5, with an arm 6 thereon and by which it is mounted for limited swinging motion about a post 7 in the base, the hole 8 in the arm being slightly oblong to provide also limited lateral motion as will be described. The rotary motion of the ring is limited, Figs. 1, 4, by a pin 9 depending from the bottom of the ring and moving in a slot 10 in the edge of the base.

The cooperating slab catcher is shown as a collar 11 with an arm 12 and hole 13 therein by means of which it is also mounted for limited swinging action on its post 14, the hole 13 being also slightly oblong for cooperative movement with the ring 5. The member 5 carries offset inwardly therefrom when assembled, and within the collar 11, two radially positioned curved posts 15, these posts and the collar 11 being slotted vertically at 16, 17 respectively to register with each other and provide a path therethrough for the yarn 18.

The collar 11 and ring 5 are retained on their posts Fig. 1, by a locking member in the shape

of an arm 19 pivoted in the base 1 and capable of being turned about its pivot and to overhang the end of the arm 12.

Practically all of the wool and much of the cotton and silk used for thread and yarn has a small amount of oil and other substances worked into it to enable it to be used conveniently in spinning and winding under unfavorable atmospheric conditions, which would otherwise cause very serious difficulties.

There is also considerable lint and dust always present near these machines, when running. If the two thread clearing members corresponding to the numbers 5, 11 herein are constructed as in my United States Patents Nos. 1,499,929 and 1,740,242, while they are very effective, nevertheless their efficiency is affected by the accumulation of oily dust and lint on the two members 7, 9 and 11, 12 respectively in said patents, because they fit so closely one within the other as to form substantially one flat surface with no clearance.

To obviate this difficulty, I have devised the construction herein shown, where one of the thread-receiving members, the post 15, is relatively narrow or thin in cross-section, and of a radius shorter than that of the collar 11, so that the post and collar are not closely positioned adjacent each other except at one point, viz., the exact point of location of the thread slots.

This feature provides a wedge-shaped space 20 adjacent each side of each slot in the collar and posts by means of which the oily dust and lint very readily escape from the vicinity of the slots 16, 17, on the collar and posts without interfering with their free operation.

The generous size of the collar 11 also permits the fingers to be inserted therein, if desired, and a small brush, to clean dust and lint therefrom if, by any chance, they should collect therein, to a substantial degree.

When Fig. 1, a slab or other thread or yarn imperfection in its upward travel approaches and contacts with the lower side of the collar 11, the pull of the machine causes the collar 11 and ring 5 and its posts to move about their pivots 7, 14, close the respective ring and collar slots and break the thread. The operator then reties the thread and the machine again is started.

The slots in the collar 11 and post 15 are usually made of a maximum size for the thread to be used. If a smaller size is to be used, an extra slot-reducing ring 21, Fig. 7, with a narrower slot 22, is slipped over the collar 11. This collar has an arm-receiving slot 23 in its lower edge to

fit over the arm 12 of the collar 11 to hold in proper slot registering relation the extra collar 21 and the collar 11.

In some winding machines, the rail or rod 3, carrying the sub-catchers is pivoted to the front of the machine and, when the thread breaks, it releases a drop wire or stop motion device (not shown) which thereupon permits the sub catcher rail with its sub catchers to drop downwardly 10 and forwardly to substantially an upright position Fig. 1, on the machine, as the latter stops.

When this type of machine starts, it does so with a quick motion and the rail 3 with its sub catchers is thrown upwardly and rearwardly to 15 substantially the position of Fig. 2, in a curved path, with a jerk which is sufficient to cause the collar 11 and ring 5 to swing upwardly about their pivots and close the thread slots, and again break the thread before the machine gets well 20 under way.

To obviate this difficulty, I have devised the novel construction which I will describe. Just above the collar 11 there is mounted, as in ears 24 on the base 1, a locking device comprising a 25 rod 25 with an offset section 26 formed therein between the ears 22, while on one end of the rod is a crank 27 carrying a weight, as a ball 28.

In the normal position of the clearer, Fig. 2, the weight will remain in raised position and the 30 offset or collar locking section 26 on the rod will also be raised. When, however, the rail with its clearers drops, as described upon the breaking of a thread, the weight 28 swings forward, and throws the offset section 26 down 35 upon the collar 11, the locking position, Fig. 4, locking it and the ring 5 against movement about their pivots.

After the thread has been tied and when the rail and its clearers are again thrown upward 40 into operative position as described, this action causes the weight 28 to swing upward and backward to its normal position, Figs. 2, 3, but the weight does not leave its position upon the collar 11 until the clearer has reached the end 45 of its travel up the curved path to position of Figs. 2, 3, and the shock which would tend to swing the collar 11 and ring 5 upon their pivots, is over, so that there is no opportunity for the collar and ring to move about their pivots 50 and again close the thread slots and break the thread.

This automatically acting collar and ring locking device is very useful and adds very much to the effectiveness of the clearer on the type 55 of machine referred to.

60

65

70

75

The thread slot changing collar 21 which is sometimes applied to the collar 11, as described, has its rear circumferential edge cut away, Fig. 8, at 29 to permit the offset section 26 of the rod 25 to rest on the collar 11 and operate as 80 usual.

My invention is not restricted to the precise embodiment thereof herein described and illustrated.

I claim:

1. A thread clearer comprising a base, means to lock it to a machine, a clearing collar, and a clearing ring movably mounted on the base, the ring having upstanding segmental posts at circumferentially opposite points thereon, registering thread slots in the collar and posts, the collar and ring adapted to be swung out of registering position to clamp the thread when engaged by an imperfection on the thread, and collar locking means to lock the collar against swinging motion during travel of the thread clearer to operative position.

2. A thread clearer comprising a base, a clearing collar and a clearing ring concentrically positioned thereon, the ring carrying posts concentrically positioned relative to the collar but having exterior surfaces non-concentrically positioned relative thereto, the collar and ring eccentrically movably mounted on the base with registering thread slots, the collar and ring movable out of slot registering relation by engagement therewith of an imperfect thread, and a rod with a collar locking offset section therein movably mounted on the base to normally lock the collar against thread clamping motion during travel of the thread clearer to operative position.

3. A thread clearer comprising a base, a clearing collar and a clearing ring concentrically positioned thereon, the ring carrying posts concentrically positioned relative to the collar but having surfaces non-concentrically positioned relative thereto, the collar and ring eccentrically movably mounted on the base with registering thread slots, the collar and ring movable out of slot registering relation by engagement therewith of an imperfect thread, and a rod with a collar holding portion thereon to normally hold the collar against swinging action and keep the thread slots open while the thread clearer is traveling to operative position from inoperative position.

SAMUEL HYSLOP.
